ELIMINATION OF CHATTERING OR HUM IN ALTERNATING CURRENT ELECTROMAGNETS

Filed July 10, 1925

Inventor:
Charles L. Perry,
by *Alexander S. Zunt*
His Attorney.

UNITED STATES PATENT OFFICE.

CHARLES L. PERRY, OF SCHENECTADY, NEW YORK, ASSIGNOR TO GENERAL ELECTRIC COMPANY, A CORPORATION OF NEW YORK.

ELIMINATION OF CHATTERING OR HUM IN ALTERNATING-CURRENT ELECTROMAGNETS.

Application filed July 10, 1925. Serial No. 42,772.

My invention is directed to improvements whereby the customary chattering or characteristic hum of an electromagnet when operated on alternating current circuits is eliminated, and also whereby the energy required to maintain the magnetic movable element of the electromagnet in the attracted position is materially reduced.

Various expedients have heretofore been proposed and adopted to eliminate the characteristic chattering or hum of an electromagnetic device when operated on an alternating current circuit. Pole shaders are most frequently employed for this purpose and these are more or less satisfactory depending on the accuracy of the fit of the contacting surfaces of the magnetic movable element with the pole or poles of the electromagnet, and also depending somewhat on the tendency of the magnetic movable element to assume the unattracted position due to the load thereon. That necessitates a substantial energization of the electromagnet. Expedients have been adopted to insure a good fit of the said contacting surfaces, such as self aligning surfaces, and the like. However, at best, these expedients are frequently only partially successful and the characteristic objectionable hum is heard. Furthermore, pole shaders, self-aligning contacting surfaces and the like are objectionable in that special constructions are necessary and such constructions are expensive.

In accordance with my invention, the objectionable chatter or hum is eliminated by rectifying the alternating current by means of a kenotron or other suitable rectifying device so that the current supplied to the winding of the electromagnet is unidirectional. One of the important advantages of the invention is that not only is the objectionable chattering or hum eliminated but also the energy required to maintain the magnetic movable element of the electromagnet in the attracted position is materially reduced. There is ordinarily no objection to operating the electromagnetic device with alternating current so it is preferable, although not necessary, to operate the device with alternating current and then maintain the device in the operated position with the rectified current since the rectifying device or devices need thus be of relatively small capacity.

For a better understanding of the inven-

tion, reference is had to the accompanying drawing which in very simple diagram shows an embodiment of the invention in the operation and control of an electromagnetic switch.

Referring to the drawing, the electromagnet switch or contactor 10 is connected so as to be energized for operation from the alternating current source of supply 11. For convenience of illustrating the principles of the invention, the switch is shown as of the plunger type and as having an operating winding 12 and a maintaining winding 13. However, I would have it understood that the invention is not necessarily limited to plunger type electromagnetic devices, since the invention is generally applicable to electromagnetic devices having a magnetic movable element operated in response to the energization of the winding of the electromagnet. A familiar type of electromagnetic device to which the invention is applicable is the pivoted armature type of electromagnetic switch in which the armature makes abutting engagement with pole pieces of the electromagnetic structure of the device when the electromagnet winding is energized.

I would also have it understood that the invention is not necessarily limited to an arrangement in which one winding is provided for operating the device and another winding is provided for maintaining the device in the operated position, since those skilled in the art will readily appreciate from an understanding of the invention that the invention is likewise applicable to single winding electromagnetic devices in which the winding serves to not only operate the device, but also to maintain the device in the operated position. It will therefore be understood that the present arrangement has been shown merely for the purpose of illustration of the principles of the invention.

The electromagnetically operated switch 10 is of the type which is disposed to chatter or produce the characteristic hum when the same is maintained energized from the alternating current source of supply 11. In order to eliminate this chattering or characteristic hum, the thermionic rectifying devices 14 and 15 have been provided to rectify the alternating current of the source of supply 11 and supply a unidirectional current to maintain the switch 10 in the operative po-

sition. These rectifying devices are preferably of the kenotron type and although it is not necessary that they be connected as shown, nevertheless the arrangement shown 5 has the advantages in that an effective rectification of both the half cycles of the alternating current is obtained so as to obtain a unidirectional current which approaches fairly closely a continuous current. The kenotrons 10 each have a heated filament or cathode 16 and an anode 17, these parts being mounted within an evacuated container 18. The kenotron has been shown in diagrammatic form, since this is a well known device and it is therefore 15 deemed to be unnecessary to illustrate and describe the details of construction and arrangement.

The step down transformer 19 is provided for supplying a reduced potential to the maintaining winding 13 of the contactor 10 through 20 the kenotrons 14 and 15. This transformer is desirable, although not strictly necessary, since the kenotrons may be connected and employed so as to rectify the alternating current of the source 11 directly without the interposition of the step down transformer. However, the provision of the transformer makes a convenient arrangement in that the 25 heated filaments or cathodes of the kenotrons 30 may be connected across a few turns of the secondary of the transformer and thereby supply a relatively low potential for the cathode circuit.

The contactor 10 is provided with a normally closed auxiliary switch 20 and a normally open auxiliary switch 21, the arrangement being such that with the contactor in the open position as shown, the winding 12 will be energized through the auxiliary switch 40 20, and when the contactor has been closed, the auxiliary switch 20 will open its contacts and by reason of the fact that the auxiliary switch 21 has been closed during the closing 45 of the contactor, the maintaining winding 13 will be energized through the kenotrons by unidirectional current.

The operation of my invention as thus constructed and arranged and with the parts in their respective positions shown in the drawing, is as follows: In order to energize the contactor 10 to close, the master or controlling switch 22 is closed, thereby energizing the winding 12 of the contactor 10 directly across the the source of supply 11. The contactor 55 will be thus energized to close its main switch contacts 23, and when the contactor has practically completed its closing operation, the auxiliary switch 20 will be automatically opened and the auxiliary switch will be automatically closed. The opening of the auxiliary switch 20 will deenergize the operating winding 12 and the closing of the auxiliary switch 21 will energize the maintaining winding 13 through the kenotrons 14 and 15. As 60 65 before explained, these kenotrons will rectify

both of the half cycles of the alternating current source of supply and produce a unidirectional current which will have the practical effect of a continuous current so that the characteristic chattering or hum of the contactor 10 is eliminated. The kenotron 18 will block off one half cycle of the alternating current and permit the other half cycle to pass, and the kenotron 15 will block off the other half cycle and permit the one to pass. 70 75

Another important feature of the invention is that the value of the energy required to maintain the contactor in the closed position is materially less than the value which would be necessary if the maintaining energy were taken directly from the alternating current source of supply. This is of importance, particularly in large electromagnetic devices, since in such devices a substantial energization must be maintained in order to 80 minimize as much as possible the chattering or characteristic hum and this produces an objectionable heating of the winding device and furthermore, is wasteful of power. When the pilot switch 22 is opened, the electromagnetic switch 10 is deenergized and permitted to assume its normal open position, the various parts then being in their respective positions shown in the drawings. When this switch 22 is opened, the transformer 19 as well as the kenotrons 14 and 15 and the contactor 10 are completely disconnected 90 from the supply circuit. 95

What I claim as new and desire to secure by Letters Patent of the United States, is: 100

1. In combination, an alternating current source of supply, an electromagnetically operated device having an electromagnet connected to be energized with alternating current from said source and including a magnetic movable element which is operated upon the energization of said electromagnet from said source, the said electromagnet being disposed to chatter or hum when alternating current energization thereof is maintained, 105 rectifying means for changing the current of said source to a unidirectional current source of supply for said electromagnet, and switch mechanism for changing the connection of the electromagnet after the initial energization thereof from said source to said rectifying means and thus reduce the energy necessary to maintain said device in the operated position thereof and prevent the said chattering or hum. 110 115

2. In combination, an alternating current source of supply, an electromagnetically operated device having an electromagnet connected to be energized with alternating current from said source and including a magnetic movable element operated thereby upon the energization of the electromagnet from said source, the said electromagnet being disposed to chatter or hum when alternating current energization thereof is maintained, 120 125 130

means for rectifying both half cycles of the
said alternating current source to provide
a unidirectional current source of supply for
said electromagnet, and switch mechanism
5 for changing the connection of the electro-
magnet after the initial energization thereof
from said source to said rectifying means
and thus reduce the energy necessary to main-
tain said device in the operated position there-
10 of and prevent the said chattering or hum.

3. In combination, an electromagnetically
operated device having an electromagnet, in-
cluding a magnetic movable element oper-
ated thereby upon the energization of the
15 electromagnet, an alternating current source
of supply, thermionic rectifying means in-
terposed between the said source and said
electromagnet to supply a unidirectional en-
ergizing current to the electromagnet, and
20 switch mechanism and connections whereby
the said electromagnet is energized initially
from said source to operate said element and
the element is maintained in operated posi-
25 tion by the unidirectional current supplied
by said rectifying means to thereby reduce
the energy necessary to maintain said device
in the operated position thereof and prevent
the chattering or hum of said electromagnet.

4. In combination, an electromagnetically
20 operated device having a winding and a mag-
netic movable element, an alternating cur-
rent source of supply, thermionic rectifying
means for changing the alternating current
of said source to a unidirectional current, and
35 means including switch mechanism and elec-
trical connections through which the said
winding is energized initially from said
source to effect operation of said device and
then the said winding is energized through
40 said rectifying means to maintain the device
in the operated position, whereby the chatter-
ing or hum of said device which would occur
if the device were maintained energized by
the alternating current of said source is pre-
45 vented and the current necessary to maintain
said device in the operated position is re-
duced.

5. In combination, an alternating current
source of supply, a movable magnetic mem-

ber, an electromagnet having an operating
winding for magnetically operating said 50
member from one position to another position
upon the energization of said winding from
said alternating current source of supply and
a holding winding for magnetically holding
said member in said other position, and alter- 55
nating current to direct current rectifying
means connected between said alternating
current source of supply and said holding
winding for supplying unidirectional ener-
gizing current to said holding winding. 60

6. In combination, an alternating current
source of supply, an alternating current to
direct current rectifying device, an electro-
magnet having two windings and a movable
70 magnetic member, and switching mechanism
and electrical connections through which one
of said windings is energized directly from
said alternating current source of supply for
magnetically operating said magnetic mem- 75
ber from one position to another position and
the other of said windings is energized from
said alternating current source of supply
through said rectifying device for mag-
netically holding said magnetic member in
said other position.

7. In combination, an alternating current
source of supply, an alternating current to
direct current rectifying device, an electro-
magnet having an operating winding con-
nected to be energized from said alternating 80
current source of supply and a holding wind-
ing connected to be energized from said
rectifying device, a movable magnetic mem-
ber arranged to be operated from one po-
sition to another position under the mag- 85
netic influence of said operating winding and
to be held magnetically in said other posi-
tion by said holding winding, and switching
means associated with the magnetic member
for deenergizing the operating winding when 90
the magnetic member is held under the mag-
netic control of the holding winding and
thereby reduce the energy consumption of the
electromagnet.

In witness whereof, I have hereunto set 95
my hand this 9th day of July, 1925.

CHARLES L. PERRY.
